DESTATICIZING PROCESS

Charles Kilbourne Bump, Hampden, and Harold F. Park, East Longmeadow, Mass., assignors to Monsanto Chemical Company, St. Louis, Mo., a corporation of Delaware

No Drawing. Application April 4, 1950.
Serial No. 154,002

7 Claims. (Cl. 250—106)

1

This invention relates to processes for rendering non-conductive materials resistant to the development of electrical charges by static excitation and to the materials so treated. More particularly, the invention relates to destaticized non-conductive materials and to a process for destaticizing non-conductive materials by radioactive means.

Non-conductive materials such as glass, porcelain, cellulose films and webs, cellulose derivative articles, synthetic resin articles, etc. easily acquire a static charge. The charge may become strong enough to give a disconcerting jolt to an individual who discharges it by bodily contact. Moreover, the static charge causes dust and lint to accumulate on the surface of the non-conductive material.

Many means for rendering non-conductive materials resistant to static excitation have been proposed most of which depend either on operating under conditions of controlled humidity, or on the incorporation of hygroscopic material into the electrically non-conductive materials. It has also been observed that exposure to radioactive materials will destaticize non-conductive materials for short periods of time.

One object of this invention is to provide electrically non-conductive materials which are resistant to the development of electrical charges by static excitation.

Another object is to provide a process for rendering electrically non-conductive materials resistant to the development of electrical charges by static excitation.

A particular object is to provide a process for destaticizing organic plastic materials.

These and other objects are accomplished by subjecting electrically non-conductive materials to the radiation of a mixture of a radioactive material with boron or beryllium.

A simple and effective test for static electricity charges on the non-conductive materials is as follows:

Place dry cigarette ashes on a smooth insulated wooden surface in an atmosphere having a controlled relative humidity of about 20%, rub the non-conductive material vigorously with a piece of soft cloth and then bring the rubbed surface to about $\frac{1}{8}$ " from the cigarette ashes. Even a slight charge will cause the ashes to fly to the non-conductive material and adhere thereto.

The following examples are given in illustration and are not intended as limitations of the

scope of this invention. Where parts are mentioned they are parts by weight.

Example I

5 An aqueous solution of radium bromide containing 10 parts of combined radium is slurried with 300 parts of powdered beryllium. The slurry is then dried by heating at about 180° C. and the dried mixture is densified in pellet form. The pellet is then placed in a brass capsule and the capsule is imbedded in a block of paraffin. The dimensions of the paraffin are such that a layer of about 4 inches of paraffin surround the entire capsule. This paraffin enclosed capsule is then used for destaticizing non-conductive materials by placing it in close juxtaposition thereto. Flat discs of polystyrene containing about 0.1% of zinc stearate, polyvinyl chloride containing about 0.2% of tri-
10 phenyl stibine become destaticized after about 1 hour in contact with the paraffin block containing the radioactive capsule. When tested by the cigarette ash test, no amount of rubbing caused the development of electrostatic charges
15 thereon. The antistatic properties remain un-
diminished for more than a year.

In contrast to the treated discs of the example, untreated discs of the same materials picked up a strong electrostatic charge with but slight rubbing. A polystyrene disc, for example, picks up a strong enough charge to attract dry cigarette ashes from a distance of more than $\frac{1}{2}$ ".

Example II

Example I is repeated except that powdered boron is used instead of beryllium. The results are substantially the same and the resistance to the development of an electrostatic charge remains effective over long periods of time.

If a disc of polystyrene is subjected to the direct action of the radiation from radium bromide, it quickly becomes destaticized but the effect of the radiation fades rapidly and disappears almost entirely within 2 or 3 hours.

Example III

Ten pieces of platinum foil coated with polonium are superimposed and placed between plates of boron carbide. The laminar structure thus made is inserted into a thin-walled brass box and the box placed in a graphite container having walls about 3 inches thick. The ratio of polonium to combined boron is about 100:400 on a weight basis. A sheet of polyvinyl chloride containing a small amount of a phosphotungstate dye becomes completely destaticized

after exposure to the radiation from the graphite container. The effective resistance to the development of electrostatic charges remains unchanged for more than a year.

Example IV

An aqueous solution containing thorium tetrachloride and boron bromide in proportions equivalent to 100 parts of combined thorium and 300 parts of combined boron is dried by gentle heating. The dried material is then pelletized and enclosed in a brass capsule which is in turn enclosed in a substantially pure polystyrene container having walls four inches thick. Non-conductive materials including paper, polystyrene and polymerized methyl methacrylate, each of which contain small amounts of a zinc salt, are rendered impervious to the development of electrostatic charges by short exposure to the polystyrene enclosed radioactive material.

The destaticizing agents of this invention are combinations of radioactive materials with boron or beryllium or a mixture of boron and beryllium. Among the radioactive materials which may be used are ionium, radium, radon, polonium, protactinium, thorium, actinium, and mixtures thereof. The radioactive materials may be used in their elemental form or in the form of their organic or inorganic derivatives. The destaticizing agent may be in the form of an intimate mixture of the radioactive material with the boron or beryllium or the latter may be interposed between the radioactive material and the non-conductive object so that the radiations must pass through the boron or beryllium before reaching the non-conductive material. As shown in the examples, the intimate mixture may be obtained by dissolving water-soluble salts of each of the components in water and then evaporating the water or by dissolving a water-soluble salt of the radioactive element in water and forming a slurry with pulverulent boron, beryllium or insoluble derivatives thereof. The ratio of radioactive material to boron or beryllium should be regulated on the basis of the radioactive element and elemental boron or beryllium. For every 100 parts of radioactive element, either alone or chemically combined, there should be from 100 to 1000 parts of elemental boron or beryllium either alone or chemically combined.

Other elements than boron and beryllium are either inoperative or so difficult to employ that they are useless in the process of this invention. Boron or beryllium may be used per se or they may be used in the form of their organic or inorganic derivatives. The insoluble derivatives may be used in pulverulent form or in the form of thin films or sheets.

The combination of the radioactive material with the boron or beryllium is conveniently enclosed in a thin-walled metal container such as a brass or platinum container which is transparent to the radiations of the radioactive combination and which does not alter the properties of said radiation. However, such a container is not an absolute necessity since the radioactive composition may be placed directly in the hydrocarbon casing.

The radioactive composition must be enclosed in a casing having walls from 2 to 6 inches thick, said casing being made of carbon or a hydrocarbon material. The hydrocarbon may be aliphatic or aromatic, should be solid at room tem-

perature and should be substantially pure. Thus, materials such as graphite, paraffin, polymers of ethylene, isobutylene, styrene, etc. may be used providing these material are substantially pure and free from metallic elements.

In order for the radiation from the radioactive compositions to accomplish the destaticizing action, there must be present in 100 parts of the non-conductive materials at least 0.05 part of certain metals either in the elemental form or chemically combined. Among the most effective metals are antimony, zinc and silver. Less effective metals are tin, calcium, scandium, titanium, selenium, strontium, zirconium, indium, cerium, tellurium, gadolinium, terbium, thulium, tantalum, tungsten, osmium, iridium, mercury and lead. Since many dyestuffs, especially mordant dyes, lubricants, stabilizers and pigments contain sufficient amounts of one or more of the effective metals, it frequently is not necessary to modify the non-conductive materials to insure incorporation of an activating metal. The incorporation of small amounts of the activating metals or their derivatives in non-conductive materials which do not contain them is generally accomplished with ease.

The radioactive compositions of this invention retain their effectiveness for many years. The amount of the compositions used determines the exposure time necessary to render the non-conductive material impervious to electrostatic excitation. A large amount of the radioactive composition spread thinly over a large area may be used to destaticize sheets and continuous lengths of non-conductive materials. If the radioactive composition is concentrated in a small area, the radiations therefrom will quickly penetrate relatively thick objects. These thick objects may then be molded, carved, machined, etc. and yet the new surfaces thus exposed will still be destaticized.

The process of this invention is applicable to all electrically non-conductive materials which contain the minimum amounts of the activating metals. Among the materials which may be treated are glass, wood, paper, natural and synthetic organic materials such as regenerated cellulose, cellulose ethers and esters, natural or synthetic rubber, organic plastics such as phenolic resins, urea resins, melamine resins, polystyrene, polyethylene, vinyl chloride polymers and copolymers, polymers and copolymers of other vinylidene compounds, etc. The non-conductive materials may be in the shape of sheets, rods, tubes, fibers, molded and extruded designs, etc.

The process of this invention is advantageous in that it provides a quick method for rendering electrically non-conductive materials resistant to electrostatic excitation over a relatively long period of time.

What is claimed is:

1. A process which comprises placing radioactive material in substantial contact with a substance from the group consisting of elemental and chemically combined boron and beryllium, thereafter embedding the radioactive material and said substance in a casing having walls from 2 to 6 inches thick, said casing comprising a solid material taken from the group consisting of carbon and hydrocarbons, and subjecting a non-conductive material to the radiations emanating from the casing, said non-conductive material containing at least 0.05% by weight of a substance from the group consisting of elemental

and chemically combined zinc, silver, antimony, calcium, scandium, titanium, selenium, strontium, zirconium, indium, tin, tellurium, cerium, gadolinium, terbium, thulium, tantalum, tungsten, osmium, iridium, mercury and lead.

2. A process as in claim 1 wherein the radioactive material is radium bromide.

3. A process as in claim 1 wherein the radioactive material is polonium.

4. A process as in claim 1 wherein the substance associated with the radioactive material is beryllium.

5. A process as in claim 1 wherein the substance associated with the radioactive material is boron.

6. A process as in claim 1 wherein the non-conductive material is an organic polymer.

7. A substantially permanently destaticized non-conductive material comprising a non-conductive material containing at least 0.05% by weight of a substance taken from the group consisting of elemental and chemically combined zinc, silver, antimony, calcium, scandium, titanium, selenium, strontium, zirconium, indium,

tin, tellurium, cerium, gadolinium, terbium, thulium, tantalum, tungsten, osmium, iridium, mercury and lead, said non-conductive material having been subjected to the radiation of a radioactive material associated with a substance taken from the group consisting of elemental and chemically combined boron and beryllium, said radioactive material being embedded in a casing having walls from 2 to 6 inches thick and said casing comprising a solid material taken from the group consisting of carbon and solid hydrocarbons.
